UNITED STATES PATENT OFFICE.

DAVID D. GORDON, OF CHICAGO, ILLINOIS, ASSIGNOR TO THE YOST ELECTRIC MANUFACTURING COMPANY, OF TOLEDO, OHIO, A CORPORATION OF OHIO.

SWITCHING MECHANISM.

1,190,888.

Specification of Letters Patent. Patented July 11, 1916.

Application filed February 2, 1915. Serial No. 5,729.

To all whom it may concern:

Be it known that I, DAVID D. GORDON, a citizen of the United States, residing at Chicago, in the county of Cook and State of Illinois, have invented a certain new and useful Improvement in Switching Mechanism, of which the following is a full, clear, concise, and exact description, reference being had to the accompanying drawings, 10 forming a part of this specification.

My invention relates to switching mechanism and has for its object the provision of a simplified switching mechanism adapted to give a quick make and break between 15 switching terminals for an electric circuit.

The structure of my invention can be confined within very small space, is readily operable by means of a rotatable element, although of course not so limited, and for 20 this reason lends itself particularly well for instance to serve as the switching mechanism for sockets. In explaining my invention in this application I am setting it forth more in detail as applied to a socket.

25 I show in connection with the accompanying drawings two embodiments which my invention may take in its application to sockets.

In the drawing Figure 1 is a longitudinal 30 sectional view of a socket constructed in accordance with my invention; Fig. 2 is a partial sectional view on line *a*—*a* of Fig. 1; Fig. 3 is a detail perspective view of the fingerhold and crank; Fig. 4 is a sectional view 35 on line *b*—*b* of Fig. 2; Fig. 5 is a perspective view of the switch element; Fig. 6 is a sectional view on line *d*—*d* of Fig. 1; Fig. 7 is a sectional view similar to that of Fig. 6 showing a modified form, and Fig. 8 is a sectional view 40 on line *e*—*e* of Fig. 7.

My improved device as set forth in Figs. 1, 2, 3, 4, 5 and 6 is shown in connection with a socket having the annular contact element 1 and the central contact 2. The annular contact element 1 is preferably connected 45 through the agency of a stud 3 and nut 4 with an incoming conductor 5. The incoming conductor 6 as shown more clearly in Fig. 6 is connected by means of a stud 7 with a stationary spring 8 and the central contact 2 is in direct electrical association 50 with a second stationary switch spring 9. The circuit is to be completed between the elements 8 and 9 and this is done by a mov-

able switch element 10 having the legs 11 and 12, which switch element 10 is pivoted upon a stud 13 mounted in the insulating portion 14 of the socket. The switch element 10 is to be moved periodically into its circuit opening or closing position by snap action through the agency of a crank 15 which is under the control of a knob or fingerhold 16. The knob 16 is rotatable in either direction of rotation and has a sleeve 17 into which the crank 15 projects, this 65 crank 15 having at that portion 18 thereof which projects into the sleeve 17 a cut away portion which is adapted to coöperate with a projection 19 pushed into the sleeve so that there is a certain amount of lost motion between the knob 16 and the crank 15 in order to permit of snap action as will presently appear. The crank 15 although substantially circular in cross-section throughout the major portion of its length has however a flattened portion 20 very elongated in cross-section as shown more clearly in Figs. 1 and 3. This distorted portion 20 of the crank is designed to coöperate with a suitable recess within the arm 11 which recess consists 70 of a substantially circular portion 21 and a second substantially circular portion 22 united by a narrow passage 23. The distorted section 20 of the crank can only pass through the narrow passage 23 when the 75 sides of this portion 20 are substantially parallel to the sides of the narrow passage 23. It will be understood of course that the section 20 is of such a size that it may be accommodated upon rotation very readily 80 within either of the portions 21 or 22 of the recess within the arm 11. It will be apparent from this that the switch element 10 can move from the full to the dotted position of Fig. 1 or vice versa only when there 85 is substantial alinement of the element 20 with the sides of the slot 23. In order to effect the snap action movement of the switch element 10, I provide a pair of springs respectively the spring 24 and the 90 spring 25. One extremity of each of these springs is curved as shown more clearly in Fig. 1 and so arranged that these springs are upon opposite sides of the crank 15. The springs are then coiled about the stud 13 so 95 that the spring 24 has a protruding portion 26 bearing against the bridge portion of the element 10. The spring 25 has a protrud-

ing extremity 27 impinging also against the bridge portion, but on the opposite side of the stud 13.

Now it will be apparent of course that if the parts are in the position shown in Fig. 1, the spring 24 being held downwardly by the crank 15, that then the extremity 26 of the spring 24 holds the switch element 10 into engagement with the switching springs 8 and 9. Assuming now that it is desired to move the switch element 10 from the full position of Fig. 1 to the dotted position of Fig. 1 when the circuit through the switch springs 8 and 9 is broken. Under these conditions the crank by means of the knob 16 is rotated in either direction of rotation. The initial rotation of the crank will place the section 20 out of alinement with the slot 23 so that the said element 10 is prevented from movement about its stud 13. A continued rotation of the crank however places the spring 25 under tension so that its extremity 27 tends under great pressure to rotate the element 10 in a clockwise direction about its pivot 13. This tendency to rotate said element 10 increases as the crank is being rotated and continues until such a time as there is alinement between the element 20 and the slot 23. At this time the spring 25 is free to exert its pressure to rotate the element 10 by snap action into the position shown by the dotted lines in Fig. 1. As the element 10 is pivoted the slot 23 of course would tend to slightly rotate the crank 15 as the arm 11 moves from its full to its dotted position, but this is done readily and cannot be prevented by the operator because there is the lost motion connection between the sleeve 17 and the stem 18 as previously explained. Thus the circuit through the elements 8 and 9 is opened by snap action. Similarly the circuit through these elements 8 and 9 can be closed by snap action, if the crank 15 is again rotated in either direction of rotation.

Referring more particularly to Figs. 7 and 8, I show a modified form in which the knob and crank retain substantially their characteristics but in which the switch element 10^a is pivoted upon an axis at right angles to the axis of the crank. The springs 24^a and 25^a are similarly mounted upon the stud 13, but these springs have converging extremities 28 and 29 which run parallel to each other and are on opposite sides of the crank 15. The restricted portion 20 of the crank again co-operates with a slotted portion 30 of the element 10^a, which slotted portion has substantially the slot provided for the arm 11 in the device shown in Fig. 1. It will be seen from this that the device is very flexible in that it can accommodate itself to various structures so that the manual actuating device may act upon it from different positions and still maintain the

same simplicity of structure and small number of moving parts.

From what has been described the nature of my invention will be readily clear.

Having however thus described two specific forms which my invention may take, what I broadly claim as new and desire to secure by Letters Patent is:—

1. An electric switch mechanism having a rotatable control part, a pivoted switch piece shiftable across the axis of rotation of said part from one side to the other thereof, the axis of said control part being substantially at right angles to the axis of said piece, a yielding connection between said part and piece, said connection effecting a snap action movement of said piece when the control part is rotated in either direction, and means controlled both by said part and said piece to at times prevent movement of said piece.

2. An electric switch mechanism having a rotatable control part, a pivoted switch piece shiftable across the axis of rotation of said part from one side to the other thereof, the axis of said control part being substantially at right angles to the axis of said piece, a yielding connection between said part and piece, said connection effecting a snap action shifting movement of said piece when the control part is rotated, and means controlled both by said part and said piece to at times prevent movement of said piece.

3. A switch movement having a rotatable control part, a movable switch piece, a pair of springs interposed between said part and piece whereby upon rotation of said control part in either direction of rotation motion is transmitted from said part to said piece to move it from either one of its limiting positions to the other by snap action, said springs being mounted intermediate their ends, one end of each spring abutting said piece, and the other end of each spring engaging said part, and means controlled by said part to at times prevent movement of said piece, said means including relatively movable interlocking elements.

4. A switch movement having a rotatable control part, a pivoted switch piece, a pair of springs interposed between said part and piece whereby upon rotation of said control part in either direction of rotation motion is transmitted from said part to said piece, to move it from either one of its limiting positions to the other by snap action, said springs being mounted intermediate their ends, one end of each spring abutting said piece, and the other end of each spring engaging said part, and means controlled by said part to at times prevent movement of said piece.

5. A switch movement having a rotatable control part, a movable switch piece, a pair of springs interposed between said part and

piece whereby upon rotation of said control part in either direction of rotation motion is transmitted from said part to said piece to move it from either one of its limiting positions to the other by snap action, said springs being mounted intermediate their ends, one end of each spring opposingly abutting said piece, and the other end of each spring opposingly engaging said part, 10 and means controlled by said part to at times prevent movement of said piece, said means including relatively movable interlocking elements.

6. A switch movement having a rotatable control part, a pivoted switch piece, a pair of springs interposed between said part and piece whereby upon rotation of said control

part in either direction of rotation motion is transmitted from said part to said piece, to move it from either one of its limiting positions to the other by snap action, said springs being mounted intermediate their ends, one end of each spring opposingly abutting said piece, and the other end of each spring opposingly engaging said part, 20 and means controlled by said part to at times prevent movement of said piece.

In witness whereof, I hereunto subscribe my name this 18th day of December A. D., 1914.

DAVID D. GORDON.
